UNITED STATES PATENT OFFICE.

ERICH KÖNIG, OF GROSSHESSLOHE, NEAR MUNICH, GERMANY, ASSIGNOR TO KUCHLER-
GESELLSCHAFT FÜR HYGIENISCHE MILCHVERSORGUNG M. B. H., OF MUNICH,
BAVARIA, GERMANY.

MILK-CAN.

1,051,121.

Specification of Letters Patent. Patented Jan. 21, 1913.

Application filed October 22, 1911. Serial No. 656,268.

To all whom it may concern:

Be it known that I, ERICH KÖNIG, a subject of the Emperor of Austria-Hungary, and residing at Grosshesslohe, near Munich, 5 Bavaria, German Empire, have invented certain new and useful Improvements in Milk-Cans, of which the following is a specification.

The present invention has reference to improvements in milk-cans, and relates more specifically to a can for shipping milk and for retailing the contents directly from it, without first pouring them into another vessel, and the invention particularly consists 10 of means for stirring the milk every time a quantity of it is drawn, in connection with a tap and operating valve therefor, whereby the results of wearing down of the valve parts, leaking and rattling, is effectively 15 prevented, the operative parts being so constructed and arranged, that they can readily be removed from the can for cleaning and repairing or the like purposes.

In order to make my invention more 20 readily understood, I will now describe it with reference to the accompanying drawings, in which—

Figure 1 represents a sectional elevation through one construction of can, embodying 25 my invention. Fig. 2 shows a fragmentary section through another form of construction.

Like parts are denoted by like letters of 30 reference.

Referring first to Fig. 1, the can A carries on its raised bottom B the seat portion c² for the valve plug c, running out into the curved discharge tube k into which the tap (not shown) is to be screwed. In the lower part 35 of the plug is provided a safety valve d, in the form of a wing-diaphragm, which prevents any fraudulent introduction of foreign matter from below through the opened valve c into the once sealed can. The valve 40 plug is secured to the lower end of the stirrer rod a, which carries stirring vanes b, so constructed that they readily pass through the restricted neck g of the can and that the stirring action of the upper vane is opposed 45 to that of the lower one. The shape of the vanes, furthermore, is such that, upon the stirrer rod being turned backward for closing the tap, only a very slight stirring action is produced. The reduced upper end of 50 the rod a is guided in a nut or perforated

cap i, which screws into the bushing f¹ secured to the cover f. A compression spring e is interposed between the neck of the rod a and the nut i, whereby upon the cover being put-on the wear and the play of the valve parts is counteracted, so that rattling and leaking is prevented. The nut i is sealed together with the rod a to the bushing f¹ during shipping. The vanes of the stirrer are so disposed on the rod a relative to the valve plug, that, on rotating the rod by means of a wrench l (Fig. 2) fitting the countersunk head f², the passages of the valve register only after the vanes have performed a certain stirring operation. Stop means c³ prevent the parts from being rotated too far.

In the construction shown in Fig. 2, the seat portion e¹ of the disk-valve c⁴ consists of more or less elastic material, such as hard rubber, caoutchouc or the like, and the stirrer rod a is screwed at i¹ into a socket i² provided in the cover f of the can, so that, upon rotation of the rod by means of the wrench l, the valve is opened or closed respectively. The means for coupling rod and 75 valve disk together, which preferably consists of a cotter or split pin e³ inserted through the respective parts, is so disposed, that the valve will open only after the stirrer has come into operation.

d denotes the safety disk, as described already with reference to Fig. 1.

In both constructions shown and described, there are provided in the upper end of the stirrer rod and the respective cover parts, air passages h, h¹, which are placed into or out of communication with one another, according to the position of the valve.

What I claim is:—

1. In a milk can, the combination of a receptacle for the liquid, a cover thereto, a discharge port in said receptacle, a rotary valve controlling said port, means in connection with said valve for preventing tampering with the contents in said receptacle, a stirrer operatively connected below to said valve and above journaled in said cover, means for admitting air into said receptacle during discharge of liquid, and means for rotating said valve through a limited distance only.

2. In a milk can, the combination of a supply receptacle, a cover thereto and a discharge port therein, a tampering-proof valve controlling said port, a stirrer in said receptacle comprising a rod and vanes.

thereon, means operatively connecting said stirrer rod and said valve in such manner that the former operates somewhat prior to the latter, and means for elastically journaling said stirrer in said cover.

3. In a milk-can, the combination with a cover and a discharge port in the bottom of the can, of a stirrer rod, vanes thereon of different inclinations, means for rotatably journaling said stirrer in said cover, means for limiting its rotary movement, and means for operating it from without; a valve controlling said discharge port and actuated

by said stirrer rod; and means for admitting air into the can in the "open" position of said valve, said parts being so interconnected that the stirrer is operated before the passages in the valve register, substantially as set forth.

In testimony whereof I affix my signature in presence of two witnesses.

ERICH KÖNIG.
